SURGICAL SPLINT

William E. Gazeley, Richard W. Meysner, and
Fritz P. Graul, Schenectady, N. Y.

Application June 25, 1951, Serial No. 233,432

8 Claims. (Cl. 128—88)

1
This invention relates to surgical splints or orthopedic braces and in particular to an improved shoulder brace.

In the past, one treatment for the repair of a weakened shoulder, as caused, for example, by poliomyelitis or other nerve lesions, has been to immobilize the arm in an elevated position relative to the body. A conventional device for such treatment is an airplane type splint or plaster cast which usually comprises a body portion and an arm portion with the arm portion elevated to a near horizontal level by means of a strut joining the elbow of the arm portion to the body portion.

The arm is maintained in an elevated or near horizontal position to prevent overstretching of the deltoid muscle which controls vertical abduction (elevation) of the arm; that is, if an arm is permitted to dangle from a weakened shoulder for a considerable length of time, the muscle controlling the elevation of the arm is stretched beyond its elastic limit to the point where it may become permanently unable to regain its function.

When the arm is immobilized in an elevated position, however, the deltoid muscle is maintained within its normal length, and it may be restored to a varying degree of function through exercise after the maximum amount of regeneration of the nerve has been obtained.

It is to be understood, of course, that there is a parallel relationship between a muscle and the nerve which controls its operation. The nerve is the signaling device that actuates the muscle. A paralyzed deltoid muscle, for example, which is common in poliomyelitis is a result of damage to the nerve which controls the operation of that muscle.

In supporting a shoulder in an airplane splint or cast to prevent overstretching of the deltoid muscle, other uninvolved shoulder and arm muscles are rendered weak through lack of use. For example, the pectoral and serratus muscles which produce abduction and adduction in the horizontal plane (movement forward and backward relative to the body) become flabby through their immobilization.

While an airplane type splint or cast is of assistance in the regeneration of function to a nerve and muscle, the regeneration is accompanied by a varying amount of discomfort. Consider the bulky plaster cast, for example; it is a cumbersome, uncomfortable structure producing pain and irritation to the wearer through its sheer weight. It is a structure that limits not

only the movement of the arm, but also of the patient, its weight rendering him semi-ambulatory.

An ideal treatment for a damaged deltoid muscle is to provide an elevated support for the arm which would permit limited movement in all directions. Such a support would enable the arm to be exercised, thereby giving tone to the unaffected muscles while waiting nerve regeneration to the paralyzed muscles.

In considering a support which permits limited movement in all directions, it must be remembered that during the period that the shoulder muscles are weak, an arm should not be rotated in the horizontal plane too far to the rear of the body; otherwise the shoulder joint may be partially dislocated forwardly (a condition known as anterior subluxation of the shoulder joint).

One of the modern treatments which attempts to provide for limited movement of the arm is a device which resiliently suspends an arm from a ceiling or other overhead support. Such a suspension permits limited exercise of unparalyzed shoulder muscles and has been found to be of great assistance in restoring function to a paralyzed muscle. It has the disadvantage, however, of rendering a patient immobile during treatment. It follows that such resilient suspension has the disadvantage of permitting only periodic treatment of the patient.

The theory of paralysis treatment at present is that exercise of the paralyzed muscle should be started as early as possible, since it seems that the earlier that exercise is initiated, the greater is the rate and completeness of recovery within the limits of nerve regeneration.

The advantage of a resilient elevated suspension for an arm is that it can be moved in a vertical plane by the deltoid muscle as soon as a minimum degree of nerve regeneration is obtained. This is because the nerve regeneration does not have to be great enough to permit the arm to be moved against the effect of gravity, since this force is balanced out by the resilient suspension.

It is an object of this invention, therefore, to provide a new orthopedic brace including means for securing the same to a patient's body and for resiliently supporting an arm relative to the body to provide for limited abduction and adduction in both a horizontal and vertical plane.

It is a further object of this invention to provide a new and improved orthopedic brace which maintains the arm resiliently in an elevated posi-

tion, thereby permitting limited exercise of the deltoid muscle even before there is sufficient nerve regeneration to move the arm against the force of gravity.

It is a still further object of this invention to provide an improved orthopedic brace which resiliently supports the arm in an elevated position while limiting rearward movement of the arm relative to the body, thereby preventing anterior subluxation of the shoulder joint.

It is a still further object of this invention to provide an improved shoulder brace having means for effecting a varying degree of resilient support to an arm, thereby permitting variation in the resistance offered to adduction (depression) of the arm in a vertical plane.

It is a still further object of this invention to provide an improved shoulder brace which resiliently supports an arm in an elevated plane, thereby facilitating the performance of the normal functions, such as eating, drinking, and brushing the teeth and helping the patient to help himself, with the resultant reduction of the hospital care which he would require.

It is a still further object of this invention to provide an improved shoulder brace which provides continual resilient support for an arm whereby treatment can be given to a patient, whether he be sitting, standing or reclining.

It is a still further object of this invention to provide an improved shoulder brace which provides resilient support for an arm and which may be worn by a patient either under or over the clothing he wears.

Further objects and advantages of this invention will become apparent and the invention will be more clearly understood from the following description referring to the accompanying drawing and the features of novelty which characterize this invention will be pointed out with particularity in the claims annexed to and forming a part of this specification.

Briefly, this invention comprises an orthopedic brace having a body portion including means for securing it to a human body, an arm portion including means for securing it to a human arm, a universal joint connecting the arm and the body portions including stops to limit the degree of rearward motion of the arm relative to the body and a resilient supporting means for elevating the arm portion relative to the body portion.

In the drawings, Fig. 1 is a front elevation of the new brace positioned on a patient shown in dotted outline; Fig. 2 is a perspective view of a portion of the brace; Fig. 3 is a bottom elevation of the brace elbow joint; Fig. 4 is a front cut-away view of the brace body portion and upper arm portion; Fig. 5 is a front elevation of a lock for maintaining the brace arm portion elevated relative to the body portion; while Fig. 6 is a top section of the stop means used for limiting the rotation of the brace arm portion relative to the body portion.

Referring to the drawings, in a preferred embodiment our new brace is shown as comprising a body portion 1, an arm portion 2 which is connected by a universal joint 3 to the body portion, and a strut 4 which is employed to support the arm portion 2 relative to the body portion 1.

The body portion 1 comprises a pair of bands 5 and 6 connected by a tubular spacer 9. Each of the bands has an adjusting buckle 7, 8, respectively, and each of the bands is further provided with a covering 10 of leather padding or the like. The bands 5, 6 are made of a metal

which may be bent in conformity with the shape of the human body. Ideally, the lower band 5 is bent to conform to the waist of a person, while the upper band 6 is bent to conform to the chest. Spacer 9 is secured by brackets 11 to each of the bands 5 and 6. It is to be understood, however, that brackets 11 are simply a suggestive manner of connecting the spacer to the bands. Obviously, other means, such as screws, rivets and the like could also be employed.

Spacer 9, as shown in Fig. 4, comprises a tube or cylinder 12, a spring 13, a pair of collars 14, 15 and an adjusting screw 16 for varying the tension on spring 13. While the diameter of the tube 11 can be changed in accordance with the size of the spring required, it has been found that a steel tube having an internal diameter in the order of three-fourths of an inch is very satisfactory for use with children. To accommodate adjusting screw 16, a plug 17 having a threaded bore 18 is inserted into the lower end of tube 12. Plug 17 may be secured to tube 12 by any conventional means, such as by the setscrew 19.

Spring 13, which is housed by tube 12 is positioned between the adjusting screw 16 and collar 14. Collar 14, which has an internal diameter adapted for sliding fit with the outer diameter of cylinder 12, is biased by spring 13 to assume a normal position which produces elevation of the brace arm portion 2. To insure proper engagement between spring 13 and collar 14, a plug 20 having one diameter small enough to fit within spring 13 is positioned on top of the spring for engagement with a pin 21 which is passed completely through collar 14. With such an arrangement, spring 13 acts on plug 20, which in turn supports pin 21 to bias collar 14 away from adjusting screw 16.

A plug 22, similar to plug 20, is positioned at the lower end of spring 13 for proper engagement with adjusting screw 16.

For controlling the vertical movement of collar 14, diametrically opposite elongated slots 23, 24 are positioned in cylinder 12 to register with the ends of pin 21. The pin and slot engagement, in addition to limiting the axial movement of collar 14, also effectively prevents its rotation relative to tube 12.

The universal joint 3 which supports the brace arm portion relative to the body portion comprises a yoke 25, an arm bracket 26 and a bearing pin 27 which supports arm bracket 26 for rotation in a vertical plane relative to yoke 25.

To provide support for yoke 25 on tube 12, a plug 28 is positioned on the upper end of tube 12. Plug 28 has one diameter engageable with the bore of tube 12 and a threaded bore 29 adapted to accommodate a screw 30 which is passed axially through yoke 25. Yoke 25, in turn, has a bottom cylinder 31 having one diameter small enough to be rotatably fit within a registering bore 32 in plug 28.

Screw 30, which secures yoke 25 to plug 28, is formed to have a bearing shoulder whereby yoke 25 is free to rotate relative to plug 28 and tube 12 no matter how tightly screw 30 is driven into bore 29.

Yoke 25 further has a pair of parallel arms 33, 34 which are integral with bottom cylinder 31 and which are spaced apart a distance suitable for the bearing support of arm bracket 26. To facilitate the rotation of arm bracket 26, a bearing pin 27 is passed through suitable openings in the arm 33 and bracket 26 to be engage-

able with a threaded bore (not shown) in arm 34.

Through the use of universal joint 3, yoke 25 is rotatable relative to the tube 12 and arm bracket 26 is rotatable relative to the yoke 25. Consequently, complete freedom of motion is given to the arm bracket 26, permitting it to be moved in all planes relative to the brace body portion.

With such a structure, however, the arm bracket 26 would be free to rotate too far to the rear of tube 12, with the resultant possibility of producing an anterior subluxation of a patient's shoulder joint. To prevent this, a stop 35 is provided to limit the motion of yoke 25. In one embodiment (see Figs. 4, 5 and 6), the stop comprises a pin engageable by opposite sides of a sector; specifically a sector 36 is removed from the cylinder 31. The sector has a depth of about one-eighth of an inch and an arc conforming with the desired arm movement. A pin 37 is then embedded in the plug 28 to be engageable with the opposite sides of the sector 36. Pin 37 strikes either side of the sector 36, thereby limiting the rotation of the yoke 25 relative to tube 12.

To provide resilient support for arm bracket 26, relative to the brace-body portion 1, a strut 4 is connected from a bearing joint 38 on arm bracket 26 to collar 15 positioned on tube 12. Joint 38 can be of any conventional structure so long as it provides for rotation between strut 4 and arm bracket 26. One form of joint is illustrated particularly in Fig. 4 wherein a pair of parallel ears 39, 40 extend downwardly from the arm bracket 26 to be separated by a distance greater than the thickness of the strut 4.

A U-shaped lock 41 is then positioned so that the free-ends of its legs are located one on either side of the strut 4 between it and the ears 39, 40, respectively. The base 42 of the U-shaped lock 41 is notched to engage a space between the arms 33, 34 of yoke 25 and arm bracket 26. When properly positioned, as shown in Fig. 5, lock 41 prevents downward movement of the arm bracket 26 relative to tube 12. To lock the arm bracket 26, it is first raised above a horizontal position, and the notched base 42 of U-shaped lock 41 is placed in engagement with yoke 25. Arm bracket 26 is then lowered, but the notched base 42 pushes against yoke 25 to prevent bracket 26 from moving downwardly relative to tube 12 more than a few degrees.

At its lower end, strut 4 is connected to collar 15 by a pair of pins 43 spaced 180° apart. These pins do not pass completely across collar 15; consequently, the collar which is in bearing fit with tube 12 is free to rotate relative to the tube.

The requirement of a pair of collars 14 and 15 can now be explained. That is, to provide for rotation of the arm bracket 26 relative to the tube 12, collar 15 must be free to rotate about the tube as an axis. On the other hand, collars 14 and 15 must be biased by spring 13, but pin 21, which fits through collar 14 across the top of spring 13 and through slots 23, 24, prevents rotation of collar 14 relative to tube 12, as has been above described. By placing collar 15 above collar 14, however, collar 15 is supported by and rotatable relative to the spring biased collar 14, thereby providing the desired support for strut 4 and arm bracket 26.

With a structure as described, the expansion and contraction of spring 13 is substantially enclosed, except for the width of slots 23, 24, thereby preventing the patient's skin from being 75

pinched or his clothes from being caught in the spring.

In a conventional embodiment, an upper arm extension 44 is secured to arm bracket 26. The extension 44 preferably is interchangeable to accommodate various arm lengths.

Support is also required for the patient's elbow and lower arm. To provide this support, the extension 44 is connected to a pivot joint 45 which in turn supports a lower arm member 46. Means such as straps 47 and 48 are employed for securing the patient's arm to the extension 44 and lower arm member 46, respectively. To limit the motions of the lower arm member in accordance with the hinge limits of a patient's elbow joint, a pin 49 is provided to be engageable by a prong 50 on lower arm member 46. A wrist support 51 of a conventional form is usually connected to the lower extremity of lower arm member 46 to position a patient's hand properly during treatment.

In operation, the bands 5 and 6 are placed around the patient's body either over or under clothing and secured by means of the buckles 7 and 8. When properly secured to a patient's body, bands 5, 6 support spacer 9 and universal joint 3 for free movement of a patient's arm and shoulder joint. Strut 4 then connects arm bracket 26 to tube 12 to provide resilient support for the patient's arm without impairing the movement allowed by the universal joint 3.

This arrangement allows the arm to be exercised in accordance with regeneration of the nerves controlling its motion. That is, as the arm is strengthened, screw 16 may be tightened to increase the bias on spring 13 and the resultant force required for adduction of the arm in a vertical plane.

While this new brace structure has been described for one arm, it is obvious that a double-arm brace could be supplied merely by duplicating the parts and connecting them in mirror likeness to the other side of the brace.

While this invention has been described in accordance with the preferred embodiment, it is obvious that other modifications will occur to those skilled in the art, and it is desired to be understood, therefore, that this invention is not to be limited to the particular embodiment described, but that it is meant to cover all modifications which are within the true spirit and scope of this invention.

What we claim as new and desire to secure by Letters Patent of the United States is:

1. An improved surgical splint comprising a body portion, means on the body portion for securing the same to a patient's body, an arm portion, means on the body portion for securing the same to a patient's arm, means including a joint mounted on said body portion for supporting said arm portion for universal movement, an elongated coil spring having a movable free end, means on said body portion positioning said spring for movement of its free end parallel to the longitudinal axis of said body portion, means interconnecting said spring free end with said arm portion to bias the same in response to the movement of said free end of said spring, and screw means for axially compressing said spring to vary the tension thereof.

2. A surgical splint comprising a body portion, an arm portion, a joint mounted on said body portion for supporting said arm portion for universal movement, a cylindrical tube, means on said body portion for mounting said tube coaxially

with said joint with its axis parallel to the longitudinal axis of said body portion, an elongated coil spring having a movable free end within said tube, a collar positioned on said tube to be movable axially thereof, means interconnecting said collar and said spring free end, and means interconnecting said collar and said brace arm portion to bias the same in response to the movement of said free end of said spring.

3. A surgical splint comprising a body portion, an arm portion, a joint mounted on said body portion for supporting said arm portion for universal movement, a cylindrical tube, means on said body portion mounting said tube coaxially with said joint with its axis parallel to the longitudinal axis of said body portion, a spring including a movable free end positioned within said tube, a first collar positioned on said tube to be movable axially thereof, means interconnecting said first collar and said spring free end, a second collar juxtaposed on said tube above said first collar for axial movement therewith, said second collar being rotatable relative to said first collar, and strut means interconnecting said second collar and said brace arm portion whereby the latter is spring biased normally to an elevated position.

4. A surgical splint comprising a body portion, an arm portion, means including a universal joint interconnecting and supporting said arm portion for universal movement relative to said body portion, rotatable stop means on said portions for limiting the movement of said arm portion in a plane transverse to the axis of said body portion, a spring having a movable free end, means on said body portion mounting said spring coaxially of said joint for movement of its free end parallel to the longitudinal axis of said body portion, axial stop means positioned on said body portion for limiting the axial movement of said spring free end, and strut means interconnecting said spring free end with said arm portion to bias the same upwardly in response to the force exerted by said spring.

5. A surgical splint comprising a body portion, an arm portion, means including a universal joint interconnecting said portions and supporting said arm portion for universal movement relative to said body portion, rotatable stop means positioned on said portions for limiting the movement of said arm portion in a plane transverse to the axis of said body portion, a spring having a movable free end, means on said body portion mounting said spring coaxially of said joint for movement of its free end parallel to the longitudinal axis of said body portion, axial stop means positioned on said body portion limiting the axial movement of said spring free end, strut means interconnecting said spring free end with said arm portion to bias the same upwardly in response to the force exerted by said spring, lock means, and means releasably positioning the same between said arm portion and said universal joint thereby locking said arm portion in an elevated position relative to said body portion.

6. A surgical splint comprising a body portion, an arm portion, means including a joint connecting said arm portion to said body portion, a spring supported by said body portion coaxially of said joint for compression and expansion parallel to the axis of said body portion, a tube substantially enclosing said spring, a collar positioned about said tube to be biased by said spring,

and a strut joining said collar to said arm portion whereby the same is biased normally to an elevated position by said spring.

5 7. An improved surgical splint comprising a body portion, an arm portion, a universal joint interconnecting and supporting said arm portion on said body portion, a tube having a pair of diametrically opposite axially extending slots, means supporting said tube on said body portion, an axially compressible spring positioned in said tube, a collar, means including a diametral pin passing through said collar, said tube and through said tube slots to be in engagement with said spring thereby positioning said collar for axial movement along said tube in response to compression of said spring, screw means in said tube for adjusting the tension on said spring, and a strut joining said collar to a point on said arm portion removed from said universal joint whereby compression and expansion of said spring are transmitted through said collar and through said strut to said arm portion to bias the same normally in an elevated position relative to said body portion.

20 8. An improved surgical splint comprising a body portion and an arm portion, a universal joint mounting said arm portion on said body portion, a tube having a pair of diametrically opposite axially extending slots, means positioning said tube on said body portion, a spring positioned in said tube for axial compression and expansion, a first collar including a diametral pin passing through said tube and through said tube slots to provide for axial movement of said collar in response to compression and expansion of said spring, an adjustable screw engageable with said tube to regulate the compression of said spring, a second collar juxtaposed on said tube above said first collar to be axially movable with and rotatable relative to said first collar, a strut joining said second collar to a point on said arm portion removed from said universal joint whereby compression and expansion of said spring are transmitted to said second collar and through said strut to said arm portion to bias the same in an elevated position relative to said body portion, said universal joint including shoulders and a pin engageable therewith controlling the movement of said arm portion transverse to the axis 35 of said body portion to prevent anterior subluxation of a patient's arm, and lock means positioned on said strut to be engageable with said universal joint to lock said arm in an elevated position relative to said body portion.
